THREAD HOLDER FOR LOOMS

Application filed September 12, 1929. Serial No. 392,222.

This invention relates to improvements in thread holders for weft replenishing looms more particularly though not necessarily of the multicolor type and it is the general object of my invention to provide means whereby the weft ends extending from the reserve bobbins are held taut and substantially parallel as the bobbins move downwardly in the magazine.

It is customary in multicolor magazines to store the reserve bobbins in vertical stacks and move the bobbins from one or another of the stacks toward transfer position. The weft ends extend from the bobbins and are anchored or secured to a fixed holder to insure unwinding of the yarn from a newly transferred bobbin so that the weaving operation may continue uninterruptedly. In the form of thread holders at present in use there is a tendency for the weft ends to become slack, thereby interfering with the proper operation of the magazine at the time of replenishment. It is a further object of my present invention to provide means for holding the weft ends in spaced relation with respect to each other and also taut throughout the descent of the bobbins from the top to the bottom of the magazine.

It is a further object of the invention to employ a reciprocable bobbin carrier and combine therewith a thread holder which is given successive advance movements in the same direction each time the bobbin carrier reciprocates.

With these and other objects in view which will appear as the description proceeds, my invention resides in the combination and arrangement of parts hereinafter described and set forth in the claims.

In the accompanying drawings wherein a convenient embodiment of my invention is set forth,

Fig. 1 is a vertical section through a magazine having my invention applied thereto,

Fig. 2 is a plan view taken in the direction of arrow 2, Fig. 1,

Fig. 3 is an end elevation taken in the direction of arrow 3, Fig. 1,

Fig. 4 is a detailed end elevation on an

enlarged scale of certain of the parts shown in Fig. 3,

Fig. 5 is a perspective view of the upper end of one of my improved thread holders.

Fig. 6 is an enlarged vertical section on line 6-6 of Fig. 3, and

Fig. 7 is a view looking in the direction of arrow 7, Fig. 2.

Referring particularly to Figs. 1 and 2, I have shown a main frame 10 having 60 guided therein for vertical movement a pair of bars 11 and 12 provided with depressor fingers 13 and 14, respectively. The bars have secured thereto carriers 15 and 16, respectively, which are preferably made of 65 sheet metal and are adapted to hold the reserve bobbins.

An actuator shaft 17 is slidably mounted in a pair of spaced arms or bearings 18 projecting from the main frame 10, and has 70 secured thereto the hub 19 of an actuator arm 20. By means of mechanisms not set forth herein but shown in my co-pending application Ser. No. 212,996 the rod 17 is given longitudinal and also angular movements, 75 the longitudinal movement depending upon which shuttle is active and the angular movement to move the arm 20 downwardly from the position shown in Fig. 1 when replenishment is to take place.

Each bar has attached thereto the lower end of a tension spring 21 the upper end of which is secured to a pin 22 secured to the main frame 10. The effect of the spring is to hold the carriers 15 and 16 in raised 85 position. The lowest bobbin of each carrier has the butt thereof supported by a shelf 23 and the tip supported by a second shelf 24.

Extending from the main plate 10 is a pair of parallel rods 25 each having a bent 90 end 26. An auxiliary plate 27 is secured to the rods 25 and guides the outer end of the carriers. Each plate may have a fin 28 received by a bent portion 29 on the carrier to extend around the fin and be guided thereby.

The matter thus far described of itself forms no part of my present invention, and it is to be understood that when replenishment is to take place one or another of the fingers 13 or 14 will be depressed by the ac- 100

tuator arm, depending upon the position of the latter, and when so depressed the lowest bobbin of the corresponding carrier will be below the lowest bobbin of the other carrier, whereupon a transfrerer designated diagrammatically at 30 in Fig. 2 moves the lowest bobbin toward the shuttle S to replenish the latter, as set forth in the above identified application.

10 In carrying my invention into effect I provide a supporting block 40 shown more particularly in Fig. 6 into which extend the ends 26 of the rods 25, the block being held in position by set screw 41. Located to the 15 right of the block as shown in Figs. 1 and 4 is a vertically sliding thread holder 42 having a slot 43 through which extends one of the rod ends 26. The holder 42 has a second slot 44 through which extends a guide 20 screw 45 extended into the supporting block 40.

The outer surface of the holder 42 is provided with a series of vertically spaced notches 46 into one of which extends a spring 25 47 secured to a collar 48 by screw 49. The collar is held to the forward rod end 26 by means of a set screw 50.

Secured to the central portion of the holder in vertical alignment is a plurality of 30 spring clips 51 which are spaced apart a distance approximately equal to the diameter of the butts of the bobbins. The inner portion of the holder is provided with a plurality of ratchet teeth 52 which are preferably 35 so spaced as not to interfere with the weft ends as the latter extend to the spring clips.

In order to move the holder downwardly with a step by step motion I extend the outer portion of the carrier 16 to have a depressing finger 53 which is sufficiently resilient to be deflected laterally when moving upwardly along one of the ratchet teeth. The finger normally extends over a ratchet tooth to engage it when descending.

45 While I have described the holder which is at the front of the magazine or to the right of Fig. 4, yet it is to be understood that there is another holder designated generally at 60 which is constructed in the manner similar to the one already described. The carrier 15 is provided with a finger 61 which cooperates with the ratchet teeth 52 formed on the rear thread holder 60. In other respects the two holders have their 55 component parts designated by the same reference characters.

In operation, the magazine will be filled with reserve bobbins, each carrier being provided with bobbins carrying wefts of distinctive characters, and the thread holders 40 and 60 will be moved to their highest position, the spring detents 47 acting to retain the thread holders in raised position. The weft ends W will then be extended horizontally from the reserve bobbins and placed

between the spring slip 51 and the body of the thread holder. When completely filled the magazine will present the appearance set forth in Fig. 1, the weft ends being taut and also substantially horizontal.

When the forward carrier 16 descends to effect replenishment the corresponding ratchet finger 53 will be lowered to engage the ratchet tooth immediately thereunder. This effects a lowering of the thread holder, in this instance the forward holder 42. While in this low position the transfrerer 30 will move the lowest bobbin toward the depleted shuttle, the end corresponding thereto being held by the lowest spring clip 51 so that 70 threading of the shuttle may follow. After the transferring operation is completed the upper bobbins of the carrier 16 will fall relatively to the latter a distance equal to the diameter of one bobbin. When the carrier rises under action of its spring 21 the bobbins will be in a position lower by the diameter of a bobbin than they formerly occupied. The weft holder 42, however, is also lowered by the same amount, so the 75 weft ends will still be horizontal. During the upward movement of the carrier 16 the finger 53 moves forwardly by the cam action of the front face of the ratchet tooth thereabove, and then springs over said tooth so as to be in position to engage the 80 same upon subsequent descent.

The operations described in connection with the first transfer follows for all ensuing transfers the holder being moved down one space for each transfer so that the 85 detent 47 engages a new notch 46. After the last transfer the holder 42 will be in lowest position and when the compartment 16 is again filled the said holder will be 90 raised, the finger 53 being moved laterally to permit the upper passage of the ratchet 95 teeth without engagement therewith.

While I have described particularly the 100 operation of the forward thread holder, yet it is to be understood that the rear holder 60 operates in substantially the same way. If it is desired to have more than two stacks of reserve bobbins, a holder may be supplied for each stack. Furthermore, although I 105 have described the invention in connection with a multicolor magazine, yet it is obvious that the invention may be employed wherein but one of the carriers is employed as 110 would be the case with a single color loom.

115 It is to be understood that the bobbin to be transferred is first given a down motion with its carrier, the horizontal motion by the transfrerer 30 to a position over the shuttle, and lastly, by means of other mechanism not set forth herein but shown in my aforesaid application, a downward movement into the shuttle. It is because of the 120 fact that the bobbin is given a horizontal motion toward the lay that I am enabled 125 130

to move the thread holders downwardly to a position below the top of the lay or shuttle box.

Each carrier may have a blunt pointed thread deflector 65, see Fig. 2, between the bobbins and thread holder. The deflectors conform to the slope of the conical bobbin tips and provide an elongated path through which the weft end passes. As the bobbin leaves the carrier and moves toward the shuttle at the time of transfer, that part of the weft which previously passed around the deflector is released to provide additional slack, thereby reducing the likelihood of thread breakage. The lower end of each carrier has outlets 66 and 67 for the tips and butts, respectively, of the bobbins, the deflectors terminating above the tip outlet, as shown in Fig. 7.

From the foregoing it will be seen that I have provided a thread holder which has a step by step motion, moving to and remaining in a new position for each transfer, also, the holder is actuated by a bobbin carrier which reciprocates from a normally idle or inactive position to transfer position and then back to normal position. It will further be seen that provision is made for retaining the thread holder in any of its vertical positions and that after each transfer, although the bobbins have a relative downward movement with respect to their carriers, yet the ends extending therefrom are horizontal. Furthermore, it will be noted that the ratchet finger which cooperates with the ratchet teeth moves with the bobbin carrier and is sufficiently flexible to slide over the inclined face of the ratchet tooth so as to become operatively related thereto. Again, as shown particularly in Fig. 5, the spring clips and ratchet teeth are so disposed that the weft ends need not become entangled with the actuating fingers.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom, a bobbin carrier movable from normal non-transferring position to transferring position to move a bobbin supported thereby into transfer position, said carrier thereafter being returned to normal position, a thread holder to retain the weft ends extending from the bobbins supported by the carrier, said holder having provision for engaging the weft ends at a plurality of spaced points, and means actuated by the carrier to give the thread holder successive movements all of which are in one direction to advance the weft ends toward transfer position.

2. In a weft replenishing loom, a bobbin

carrier movable from normal non-transferring position to transferring position to move a bobbin supported thereby into transfer position, said carrier thereafter being returned to normal position, a thread holder, a plurality of devices on the thread holder to retain the weft ends of the bobbins mounted on the carrier and hold said weft ends in substantially parallel alignment, and means actuated by the carrier to give the thread holder a plurality of successive movements in the same direction to advance the weft ends toward transfer position.

3. In a weft replenishing loom, a bobbin carrier movable from normal non-transferring position to transferring position to move a bobbin supported thereby into transfer position, said carrier thereafter being returned to normal position, a thread holder movably mounted and having a plurality of devices to engage the weft ends extending from the bobbins of the carrier and hold said ends in substantial parallel relation, and pawl and ratchet elements, one of said elements movable with the carrier and the other movable with the holder, said elements effective to give the holder successive movements in the same direction by motions derived from the carrier.

4. In a weft replenishing loom, a bobbin carrier movable from normal non-transferring position to transferring position to move a bobbin supported thereby into transfer position, said carrier thereafter being returned to normal position, a thread holder movably mounted and having a plurality of devices to retain the weft ends extending from the bobbins of the carrier and hold said ends in substantially parallel relation, a pawl element supported by and moving with the carrier, a plurality of ratchet teeth on the holder to be engaged by the pawl, said carrier when moving toward transfer position causing the pawl to give the holder a movement to carry the lowest weft toward transfer position, and means to prevent reverse motion of the holder when the carrier returns to normal position.

5. In a weft replenishing loom, a bobbin carrier movable from normal non-transferring position to transferring position to move a bobbin supported thereby into transfer position, said carrier thereafter being returned to normal position, a movably mounted thread holder having a plurality of devices to engage the weft ends extending from the bobbins of the carrier and hold said ends in substantially parallel relation, pawl and ratchet elements, one of said elements movable with the carrier and the other movable with the holder, said elements effective to give the holder successive movements in the same direction by motions derived from the carrier, and means to

retain the holder against reverse motion when the carrier returns to normal position.

6. In a weft replenishing loom, a bobbin carrier movable from normal non-transferring position to transferring position to move a bobbin supported thereby into transfer position, said carrier thereafter being returned to normal position, a movably mounted thread holder, a plurality of spaced spring clips thereon to hold the weft ends extending from the bobbins of the carrier in substantially parallel relation, ratchet teeth on the holder spaced apart a distance substantially equal to the distance between adjacent clips, and a pawl supported by and moving with the carrier to engage the ratchet teeth and effect successive movements of the holder in the same direction by motions derived from the carrier.

7. In a weft replenishing loom, a bobbin carrier movable from normal non-transferring position to transferring position to move a bobbin supported thereby into transfer position, said carrier thereafter being returned to normal position, a movably mounted thread holder, a plurality of spaced spring clips thereon to hold the weft ends extending from the bobbins of the carrier in substantially parallel relation, ratchet teeth on the holder spaced apart a distance substantially equal to the distance between adjacent clips, and a pawl supported by and moving with the carrier to engage the ratchet teeth and effect successive movements of the holder in the same direction by motions derived from the carrier, the ratchet teeth being located between the spring clips with respect to the direction in which the holder moves.

8. In a weft replenishing loom, a bobbin carrier movable from normal non-transferring position to transferring position to move a bobbin supported thereby into transfer position, said carrier thereafter being returned to normal position, a movably mounted thread holder, a plurality of spaced spring clips thereon to hold the weft ends extending from the bobbins of the carrier in substantially parallel relation, ratchet teeth on the holder spaced apart a distance substantially equal to the distance between adjacent clips, and a pawl supported by and moving with the carrier to engage the ratchet teeth and effect successive movements of the holder in the same direction by motions derived from the carrier, said pawl being resilient and capable of lateral movement when in engagement with a portion of a ratchet tooth during the return movement of the carrier to normal position following a transfer.

9. In a weft replenishing loom, a bobbin carrying member having one complete re-

ciprocation for each transfer, a thread holding member to hold the weft ends extending from the bobbins in the carrier, and means carried by one member and engaging the other to give the thread holding member successive movements in the same direction to advance the weft ends toward transfer position.

10. In a weft replenishing loom, a bobbin carrying member having one complete reciprocation for each transfer, a thread holding member to hold the weft ends extending from the bobbins in a carrier, means carried by one member and engaging the other to give the thread holding member successive movements in the same direction to advance the weft ends toward transfer position, and means to retain the thread holder member and prevent movement of the same when the bobbin carrier member is completing a reciprocation thereof.

11. In a weft replenishing loom, a fixed frame, a bobbin carrier having a vertical reciprocation in the frame for each transfer, the carrier being normally raised and moving down prior to transfer to place the lowest bobbin therein in transfer position and being movable back to normal position after transfer, a thread holder slideable vertically on the frame, and means under control of the carrier to give the holder successive downward movements in the same direction, one for each transfer, the holder assuming and retaining a new position for each reciprocation of the carrier.

12. In a weft replenishing mechanism having a stack of vertically aligned bobbins, a carrier for said bobbins movable vertically and normally in raised position but depressible to a lower position to move the lowest bobbin therein to transfer, a thread holder to which are attached the weft ends extending from the bobbins, and a deflector interposed between the weft on the bobbins and the thread holder and engaging the weft ends to require said ends to assume a form other than a straight line, said deflector terminating at a point above a bobbin in transfer position, whereby when the bobbin passes to transfer position with the carrier the weft end thereof will be slackened to facilitate transfer.

13. In a weft replenishing mechanism having a stack of vertically aligned bobbins, a carrier for said bobbins movable vertically and normally in raised position but depressible to a lower position to move the lowest bobbin therein to transfer, a thread holder to which are attached the weft ends extending from the bobbins, and a deflector or interposed between the weft on the bobbins and the thread holder and engaging the weft ends to require said ends to assume a form other than a straight line, said deflector terminating at a point above a bob-

bin in transfer position, whereby when the bobbin passes to transfer position with the carrier the weft end thereof will be slackened to facilitate transfer, said deflector being rigid with and moving with the carrier.

14. In a weft replenishing loom having a series of vertically aligned bobbins which are movable toward transfer position, a carrier for the bobbins, weft ends extending from the bobbins, a thread holder to which the weft ends are secured, and a deflector for the weft ends formed as an integral part of the weft carrier and extending substantially parallel to the path of movement of the bobbins as they move toward transfer position, said deflector engaging the bobbins and weft ends intermediate the weft on the bobbins and the thread holder to give said weft ends a form other than a straight line, the weft ends passing beyond the deflector as the bobbins move to transfer position so that a weft end of the bobbin in transfer position will be slackened to facilitate transfer.

25 In testimony whereof I have hereunto affixed my signature.

ALBERT A. GORDON.
